UNITED STATES PATENT OFFICE

90,585

DESIGN FOR A HOSPITAL CARRIAGE

Frank Koenigkramer and Frederick Koenigkramer, Cincinnati, Ohio

Application October 25, 1932. Serial No. 45,579

Term of patent 14 years

To all whom it may concern:

Be it known that we, FRANK KOENIGKRAMER and FREDERICK KOENIGKRAMER, citizens of the United States of America, and residents of Cincinnati, in the county of Hamilton and State of Ohio, have invented a new, original, and ornamental Design for a Hospital Carriage, of which the following is a specification, reference being made to the accompanying drawing, forming a part thereof.

The figure is a perspective view of the device of the invention.

We claim:

The ornamental design for a hospital carriage, as shown.

FRANK KOENIGKRAMER.
FREDERICK KOENIGKRAMER.
